UNITED STATES PATENT OFFICE.

ELBRIDGE J. STEELE, OF WOLCOTTVILLE, CONNECTICUT, ASSIGNOR TO TURNER, SEYMOUR & JUDDS, OF SAME PLACE.

DESIGN FOR PLATES OF SHUTTER AND TASSEL-HOOKS.

Specification forming part of Design No. 5,274, dated September 19, 1871.

To all whom it may concern:

Be it known that I, ELBRIDGE J. STEELE, of Wolcottville, in the county of Litchfield and State of Connecticut, have invented or produced an original Design for Plates of Shutter and Tassel-Hooks, &c.; and the following is declared to be a correct description thereof.

This ornamental plate is adapted to receiving a hook upon its back for fastening shutters, or a hook projecting from its face for a tassel or cord to hang upon.

The configuration of the said plate is shown in the annexed drawing, and also the ornamental shapes applied in relief upon the surface.

The central portion *a* of said plate is elliptical in form, and the end portions *b b* are also ellip-

tical but of smaller size, and with the longer diameter at right angles to that of the ellipse *a*. The end ornaments *cc* are circular. The surface of this plate is ornamented with ribs or beads of the character shown, and the ornaments upon the ellipses at *b* are scrolls and leaflets.

I claim as my invention—

The design of the shape or configuration and surface ornamentation of the plate, substantially as described and represented.

Signed by me this 18th day of July, A. D. 1871.
ELBRIDGE J. STEELE.
